UNITED STATES PATENT OFFICE.

WILLIAM BUNTING, JR., OF BOSTON, MASSACHUSETTS, ASSIGNOR TO THE MEYER-SNIFFEN COMPANY, (LIMITED,) OF NEW YORK, N. Y.

SUPPLY-TANK FOR WATER-CLOSETS.

SPECIFICATION forming part of Letters Patent No. 329,361, dated October 27, 1885.

Application filed June 9, 1885. Serial No. 168,159. (No model.)

To all whom it may concern:

Be it known that I, WILLIAM BUNTING, Jr., of Boston, in the county of Suffolk and State of Massachusetts, have invented certain new and useful Improvements in Supply-Tanks for Water-Closets; and I do hereby declare that the following is a full, clear, and exact description thereof, reference being had to the accompanying drawings, making part of this application.

My invention relates to that kind of water-closet supply-tank apparatus in which the mechanism is operated by the action of the water-closet seat, and in which there is produced both a "preliminary" wash and an "after-flush;" and my invention has for its main objects to provide for use in this kind of water-closet apparatus means or mechanism which, while simple and efficient in construction and mode of operation, will perfectly produce the desired results of a preliminary flush or wash and an after-wash, in the proper and desired proportions as to the quantity of water employed at each flushing operation.

To these main ends and objects my invention consists in the novel devices and combination of devices which will be hereinafter more fully described, and more particularly pointed out and defined in the claims of this specification.

To enable those skilled in the art to make and use my invention, I will now proceed to describe the same, referring by letters of reference to the accompanying drawings, which form part of this specification, and in which I have illustrated my invention carried out in that form which is the best now known to me, and in which I have so far successfully practiced my improvement.

In the drawings, Figure 1 is a top view of a supply-tank apparatus made according to my invention. Fig. 2 is a vertical longitudinal section of the same, taken at the line *xx* of Fig. 1. Fig. 3 is a partial vertical section taken at the line *yy*, Fig. 1, and representing the parts in that position in which they would be when the operating-lever shall have been nearly pulled down by the depression of the closet-seat. Fig. 4 is a similar section on the line *yy* of Fig. 1, but with the parts in the positions in which they would be when the operating-

lever is rising, as it does immediately upon the releasement from occupancy of the seat of the closet.

In the several figures the same part will be found designated by the same letter of reference.

A is the tank, of the usual construction, and provided with a ball supply-cock, B, connected, as usual, with a supply-pipe, C, and provided with the ordinary lever, D, and float E, for closing the supply-cock whenever the tank shall have become filled to the proper extent.

F is the exit-pipe or discharge-nozzle of the tank, from which a pipe leads, as usual, to the bowl of the closet, and which is connected with the ordinary valve-chamber, G, with which is combined a valve, H, that is lifted and allowed to descend by gravity in a well-known manner, said valve being suspended by a rod, I, from the lifting mechanism, which latter will be presently described.

J is a siphon, (of the usual construction and arrangement,) the longer arm of which communicates with the valve-chamber, and through it with the discharge or exit nozzle of the tank. Said siphon is, however, supplied with an air-induction pipe, K, which, as shown, extends from a point near the upper end of the shorter leg of the siphon to a point where it opens upwardly immediately beneath the weighted end of the operating-lever L, which latter is formed or provided with a valvular packing device, a, that at certain times, as will be hereinafter explained, closes up the open end of said air-pipe K. The lever L is mounted in about the usual way, so that its pivotal axis M will turn freely in suitable bearing-boxes at N, and said axis M is formed or provided, as shown, with a radially-projecting arm or lug, b, which operates to depress the shorter arm of a rocking lever, c, that is pivoted, as shown, in suitable ear-pieces, d, permanently arranged for the purpose.

O is the valve-lifting lever, which is pivoted at one of its ends in ears e, and which has connected with it in a flexible manner the upper end of the valve-rod I. This valve-lever O is lifted at different times by two different means or devices, as follows: Every time the

longer arm of the operating-lever L is pulled down by the depression of the seat of the closet the free end of the valve-lever O is lifted by the upward stroke of the longer arm of the 5 rocking lever c. The latter, after having lifted the valve-lever, passes clear of the latter, allowing the latter to fall and the valve H to seat itself by gravity, while at each ascent of the longer arm of the lever L a laterally-projecting lug, f, on the inner side of the lever comes into contact with an eccentrically-pivoted block on one side of the valve-lever O, and, pressing upwardly against said eccentrically-pivoted block, carries up the valve-lever, to 10 which it is attached, thus again lifting the valve. As the ascending arm of the valve reaches its highest point, however, the pivoted block g turns on its axis in such manner as to become released from contact with the 15 lever-lug f, and permit the valve-lever to again descend, so that the supply-valve may be again closed. It will be seen that during each complete movement of the main lever L—that is, each time said lever is pulled down by the 20 descent of the closet-seat and allowed to reascend to its original position by the ascent of said seat—the valve H is lifted and allowed to fall by reason of the action of the rocking lever c, and is again lifted and allowed to fall through 25 the action of the lug f on the eccentrically-pivoted block g of the valve-lifting lever, the rocking lever c being permitted at each ascent of the longer arm of the lever L to resume the position from which it was moved when said longer 30 arm of said lever L previously descended. It will also be seen that whenever the longer arm of the lever L is pulled down, for the purpose of lifting the valve H, the outer end of the air-pipe K is opened and left open, so that 35 the siphon J cannot act to empty the contents of the tank through the valve-chamber, and so that all the water which can pass from the tank will be such in quantity as can enter the valve-chamber during the short time that 40 the valve H is off of its seat, which quantity of water will be comparatively small, but sufficient for what is called a "preliminary" wash to the bowl. Every time, however, that the valve H is lifted by the ascending movement 45 of the longer arm of the lever L the open or valvular end of the air-pipe K is closed by the packing device or valve a about at the same time that the valve H is seated, or immediately afterward, so that the siphon 50 may act in the usual manner, and continue to supply the valve-chamber G with water until the contents of the tank, down to the level of the lower end of the shorter leg of the siphon, shall have been exhausted. It will be understood 55 that by varying the elevation or location at which the inner end of the air-pipe K communicates with the siphon (so as to have this point of communication more or less below the level of the water in the tank) the amount 60 of water discharged through the valve-chamber at each preliminary wash may be regu- 65

lated or predetermined as may be desired. Of course every time the contents of the tank is discharged the ball-float E drops, as usual, and the ball-cock is opened and resupplies the 70 tank up to the level at which the ball or float will have to ascend to effect the reclosing of the cock or faucet B. The eccentrically-pivoted block g offers no impediment to the descent of the lug f when the longer arm of the 75 main lever L is pulled down to effect the preliminary flush, but simply swings very slightly at its pivotal connection, so that while the block ascends bodily and the lug f descends bodily said block and said lug will freely pass 80 by each other. When, however, (after the use of the closet,) the longer end of the lever L is allowed to ascend, the lug f, coming against one of the under inclined faces of the block g, engages itself with said block in such a 85 manner that the lug and the block are obliged to travel upwardly together with little or no relative movement until these devices are nearing the end of their upward movements, when said block g will turn (considerably) on its 90 pivot until the lug f and block g become disengaged, to permit the descent of the valve-lever, and the consequent fall by gravity of the valve H onto its seat.

Of course the precise forms shown of the 95 block g and lug f are not indispensably necessary to the mode of operation hereinbefore explained, and the shapes and sizes of other parts of the contrivance, herein shown and described, may be more or less varied without 100 changing its principle of construction or mode of operation.

It will be seen that by the combination, with the valve-lifting lever O, of the rocking lever c, operated by the arm or lug projecting from 105 the axis of the main lever, and the eccentrically-turning block g, operated upon, as described, by the lug f, projecting from the main lever, a very simple, strong, durable, and efficient contrivance is provided for use, by 110 means of which, through the simple descending and ascending strokes of the longer arm of the lever L, the tank-valve will be properly operated to produce the necessary preliminary flush and after-wash in the water-closet 115 bowl.

Having now so fully explained the construction and operation of my improved water-closet supply-tank apparatus that those skilled in the art can readily make and use my improvements, what I claim as new, and desire to secure by Letters Patent, is—

1. In combination with the valve-lifting lever O, pivoted at one end to a fixed fulcrum, and a rocking lever, c, similarly pivoted, an 125 arm or lug, b, on the axis of the main lever L, arranged and operating to throw up the longer arm of the lever c (to elevate the free end of the valve-lever) at each downward movement of the main lever L, as described, and means, 130 substantially such as described, for effecting the lifting of the free end of said valve-lever at

each upward movement of the longer arm of the main lever L, all substantially in the manner and for the purposes set forth.

2. In combination with the valve-lifting lever O, the main lever L, and suitable means for lifting the free end of the said valve-lever during each descent and each ascent of the longer arm of the main lever L, an air-pipe, K, communicating at one end with the siphon and alternately opened and closed at its other end by a suitable packing or valvular device,

which is removed from and reseated on the exposed end of said air-pipe by the said lever L, all substantially in the manner and for the purposes set forth.

In witness whereof I have hereunto set my hand this 2d day of May, 1885.

WM. BUNTING, JR.

In presence of—

JAS. TUCKER,
GEO. Z. HAMBLEN.
